AMUSEMENT DEVICE

Murry Margelith, Ocean Park, Calif.

Application March 12, 1932, Serial No. 598,465

18 Claims. (Cl. 273—101)

This invention relates to an amusement device, and it is a general object of the invention to provide a device of this character that is attractive, entertaining and commercially practical.

5 An object of the present invention is to provide an amusement device that simulates a pile driver in structure, appearance and operation.

It is another object of the invention to provide 10 an amusement device of the character mentioned that includes a hammer or weight operated by a boom or crane, and that is adapted to strike any one of a plurality of buttons controlling the dispensing or delivery of coins, tokens, or the like.

It is an important feature of the present invention that the hammer or weight is under the control or the partial control of the player so 20 that he may employ skill in an endeavor to strike any particular button with the weight.

It is another object of the invention to provide 25 an amusement device of the character mentioned that is adapted to deliver different amounts of coins or tokens when different buttons are struck or operated. This feature urges the operator or player to attempt to strike the buttons paying the largest number of coins or tokens, which buttons may be located in positions where they are more difficult to strike.

30 It is another object of the invention to provide a device of the character mentioned that is entirely automatic in its operation, and that is automatically reset for further play at the end of each operation.

35 It is another object of the invention to provide an amusement device of the character mentioned that is coin controlled, and does not necessitate the attention of an operator or attendant.

It is another object of the invention to provide 40 an amusement device of the character mentioned that may be operated a great number of times without requiring regulation or refilling of the coin or token dispensing means. The device embodies an electric actuating means that is under 45 the control of a coin or token controlled mechanism, and the coin or token containers are adapted to carry sufficient coins or tokens to permit several operations of each of the buttons.

It is another object of the invention to provide 50 a device of the character mentioned that is particularly attractive in appearance and that is simple and inexpensive in construction and operation.

55 Further objects and features of the invention will be best and more fully understood from the

following detailed description of a typical form and application of the invention, throughout which description reference will be had to the accompanying drawings, in which:

Fig. 1 is a front view of the device provided by 5 the present invention showing a portion of the transparent panel broken away to illustrate the miniature pile driver in full lines. Fig. 2 is an enlarged horizontal sectional view of the mechanism removed from the cabinet, being a view 10 taken immediately above the board. Fig. 3 is an enlarged vertical detailed sectional view taken as indicated by line 3—3 on Fig. 2. Fig. 4 is an elevation of a portion of the mechanism on the under side of the board, being a view taken sub- 15 stantially as indicated by line 4—4 on Fig. 3. Fig. 5 is a vertical detailed sectional view of the assembly illustrating it mounted within the cabinet. Fig. 6 is an enlarged horizontal sectional view taken substantially as indicated by line 20 6—6 on Fig. 3. Fig. 7 is a vertical detailed sectional view taken substantially as indicated by line 7—7 on Fig. 5. Fig. 8 is an enlarged vertical detailed sectional view taken as indicated by line 8—8 on Fig. 7. Fig. 9 is an enlarged per- 25 spective view of one of the cams showing it apart from the other portions of the mechanism. Fig. 10 is an enlarged side elevation of a portion of the mechanism, being a view taken substan- 30 tially as indicated by line 10—10 on Fig. 3. Fig. 11 is an enlarged vertical detailed sectional view of the gate mechanism controlling the discharge 35 of the coins or tokens from one of the containers. Fig. 12 is a vertical detailed sectional view of a portion of the device being a view taken as indicated by line 12—12 on Fig. 3. Fig. 13 is a vertical detailed sectional view through the clutch and winding drum taken as indicated by line 13—13 on Fig. 6. Fig. 14 is a diagrammatic view of the power means and the coin controlled 40 means governing the energizing circuit of the power means.

The amusement device includes, generally, a case or cabinet 10, a miniature boom type of pile driver 11 in the cabinet 10, means 12 for operating the pile driver 11, a plurality of buttons 13 representing the piles to be driven by the pile driver 11 and adapted to control the discharge of coins or tokens from a plurality of containers 14, a manual control means 15 whereby the operation 45 of the pile driver 11 may be controlled, a coin controlled means 16 for governing the operation means 12, and various other parts and mechanisms, the details and functions of which will be subsequently described.

The case or cabinet 10 may be varied considerably in construction and configuration without departing from the broader aspects of the invention. In the drawings I have illustrated a substantially rectangular cabinet provided with ornamented corner posts 17, and a suitable base 18. The pile driver 11 and the various other parts of the device are mounted within the cabinet 10, and the front of the cabinet, and if desired, one or more sides of the cabinet has a panel 19 of glass or transparent material so that the pile driver 11 is visible from the exterior of the cabinet. A suitable lamp 20^a may be provided within the cabinet to illuminate the interior of the cabinet 10.

15 The miniature pile driver is the active visible mechanism of the device and is mounted within the cabinet 10 in a position where it is visible through the transparent panel 19. In the particular case illustrated, the pile driver 11 is mounted on a platform 20 supported on a horizontal partition or board 21. The board 21 together with the various other parts of the mechanism are removable from the cabinet 10, as will be hereinafter described. The pile driver 11 includes a body or frame 22 rotatably supported on a base 23 through a suitable bearing 24. The frame 22 of the pile driver is mounted for rotation about a vertical axis and is provided with 20 two rigid upwardly projecting posts or masts 25. A crane or boom 26 has its lower end pivoted to the body 22 by a pin 27. The masts 25 and the boom 26 are offset forwardly from the vertical axis of rotation of the body 22. A hammer 28 or weight is suspended from the upper end of the boom 26 by a flexible line 29. The weight or hammer 28 is provided to strike or operate the buttons 13 and is preferably provided with a flat lower end to contact with the upper ends of the buttons. The weight supporting line 29 passes 30 over a pulley 30 on the upper end of the boom 26 and extends rearwardly and downwardly to operate over a pulley 31 rotatably mounted between the upper ends of the masts 25. The line 29 extends downwardly from the pulley 31 and is wound on a winding drum 32 carried by the body 22. A shaft 33 extends between spaced vertical flanges 34 on the body 22 to rotatably support the winding drum 32. The miniature 40 pile driver just described, very closely resembles a boom type of pile driver or crane mechanism, and is mounted in the cabinet 10 in a manner to be particularly attractive.

The means 12 is operable to turn the frame or body 22 of the pile driver and to operate the winding drum 32 and the boom 26 to control the weight 28. The actuating means 12 includes a suitable power means preferably in the form of an electric motor M on a board 35 seated on the bottom of the cabinet 10. Posts or supports 36 connect and space the boards 21 and 35. One lead 37 of the circuit energizing motor M is controlled by the coin means 16, while a suitable fuse 38 is provided in the other lead. The shaft of the motor M drives a vertical shaft 39 through a suitable reduction gear 40. The vertical shaft 39 extends upwardly through openings in the board 21 and the platform 20 of the pile driver, and has a worm 40a on its upper end. The worm 40a meshes with a worm gear 41 carried on a shaft 42 extending between the spaced flanges 34. Pinions 43 are provided on the drum shaft 33 and the shaft 42, and a gear 44 cooperates with the pinions 43 to provide a drive between the worm shaft 42 and the drum shaft 33. It will be apparent

how the drum shaft 33 is rotated by the motor M.

In accordance with the invention, the drum shaft 33 is slidable and the drum 32 is connected with it through a releasable clutch 45. A suitable spring 46 normally retains the shaft 33 in a position where the clutch 45 is engaged. The shaft 47 carrying the gear 44 projects from one of the flanges 34 and a cam 48 is mounted on its projecting end. The cam 48 is provided to operate or pivot the boom 26 and controls the clutch 45 to govern the winding and unwinding of the line 29 carrying the weight 28. A rearwardly projecting lever 49 is fixed on the pivot pin 27 carrying the boom 26. The cam 48 has a cam face 50 for cooperating with the lever 49 to govern the movement of the boom. The cam face has a concentric portion that cooperates with the lever 49 to hold the boom in an "up" position such as illustrated in the drawings, an inwardly extending portion rides on the arm 49 to allow lowering of the boom, and a straight tangential portion against which the lever 49 engages when the boom is lowered. The cam 48 is turned or rotated one complete revolution during each operation of the mechanism so that the boom 26 is allowed to lower through its own weight, is momentarily allowed to remain in a lowered position, and is then raised by cooperation of the cam face 50 with the lever 49, to return to a position such as shown in the drawings.

An end cam face 51 is provided on the cam 48 to engage the projecting end of the drum shaft 33. The cam face 51 is operable to shift the shaft 33 to release the clutch 45 and allow the drum 32 to rotate freely permitting dropping of the weight 28. The shaft 33 is continuously rotated during each operation of the gearing described above so that the line 29 is being wound on the drum 32 until the cam face 51 acts to release the clutch 45 to allow for the unwinding of the line 29 and the dropping of the weight 28. The cam faces 50 and 51 are related so that the weight 28 is dropped or allowed to fall when the boom 26 is in a down or partially down position. The inclination or position of the boom 26 at the time of dropping of the weight 28 may be governed by the manual control means 15 as will be hereinafter described.

The operating means 12 oscillates or turns the frame 22 of the pile driver during each operation of the device. A worm 52 is provided on the vertical shaft 39 at a point beneath the board 21 and meshes with a worm wheel 53 carried on a substantially horizontal shaft 54. A cam 55 is provided on the forward end of the shaft 54 to cooperate with a pivoted arm 56. A crank 57 is provided on the lower end of a vertical stub shaft 58 to cooperate with a notch 59 in the upper end of the pivoted arm 56. A sleeve 60 is fixed to the frame 22 of the pile driver and surrounds the vertical shaft 39 to project below the platform 21. A link 61 is pivotally connected to projecting arms 62 on the stub shaft 58 and the sleeve 60. The link 61 operatively connects the stub shaft 58 with the frame 22 of the pile driver so that turning of the stub shaft causes corresponding turning of the pile driver. A spring 63 is provided to hold the pivoted arm 56 in cooperation with the cam 55 and is operable to move the arm 56 substantially one half of its stroke during the return movement of the cam.

In the preferred form of the invention, means is provided for adjusting the stroke or movement of the arm 56. A shoe or plate 64 has one end pivoted to the arm 56 and is adapted to be en- 75

gaged by the cam 55 to cause the desired movement of the arm. An adjusting set screw 65 engages the plate 64 so that the position of the plate may be adjusted at will. The vertical shaft 39 is continuously rotated during each operation of the device and the mechanism just described provides for the swinging or turning of the pile driver. The extent and duration of turning of the pile driver 11 may be governed or controlled by the manual control means 15, as will be hereinafter described.

The buttons 13 project upwardly from the upper face of the board 21 and when struck by the weight 28, cause the release of coins or tokens T from the container 14 so that they are delivered to the player. There may be any suitable number of buttons 13 and they may be spaced or positioned as desired. In the particular case illustrated in the drawings, there are a plurality of buttons 13 arranged in spaced rows, each button being slidably vertically in a carrier 67 in an opening in the board 21. The heads of the buttons 13 project upwardly from the board 21 so that they may be readily struck by the weight 28. Springs 68 are provided in the carriers 67 to yieldingly hold the buttons in positions where their heads project above the board 21. The heads of the buttons 13 may be colored or marked as desired to indicate the number of coins or tokens 30 that are delivered or paid out when they are depressed by the weight 28. A covering 70 of felt or the like may be provided on the upper side of the board 21 around the buttons 13.

A release or discharge means is provided on the lower end of each container 14 that is operable to discharge a given number of coins or tokens, and operative connections are provided between the buttons 13 and the discharge means whereby depression of a button 13 causes the release or discharge of the tokens from one or more containers.

The containers 14 are in the form of vertical tubes projecting upwardly from the board 21. A plurality of longitudinally spaced openings 71 is provided in each of the tubular containers 14 so that their contents are visible. I have shown a row of three containers 14 projecting upwardly adjacent each end of the board 21. The upper ends of the containers 14 are open to admit the coins or tokens to be filled into them while the lower ends of the containers are supported in carriers 72 extending through openings in the board 21. The lower ends of the carriers 72 are flat and a measuring or counting gate 73 slidably cooperates with the end of each carrier. A stationary plate 74 slidably supports the lower end of each gate 73. A vertical opening 75 is provided in each gate 73 to normally register with the lower end of the opening in the container 14. The openings 75 of the several gates 73 are adapted to contain a given or definite number of coins or tokens T and the openings 75 may be of different lengths so that the different gates 73 are adapted to discharge various numbers of tokens.

The gates 73 are normally maintained in a position where the plates 74 prevent the discharge of the coins or tokens. Openings 76 offset from the containers 14 are provided in the plates 74, and the gates 73 are shiftable to positions where coins or tokens may discharge through the openings 76. Suitable troughs 77 are provided below the plates 74 to receive the discharged coins or tokens and pass them to outlet openings 78 provided in the front of the cabinet 10. Springs 79 engage around downwardly projecting lugs 80 on

the gates 73 to normally urge the gates 73 toward a position where they discharge their contents through the openings 76.

Latch means is provided to normally releasably hold the gates 73 against movement. The latch means includes pivoted latch rods 81 having fingers 82 engaging the forward ends of the gates 73. Upon turning of the latch rod 81, the fingers 82 are raised and permit shifting of the gates 73. The operating or releasing connections between the buttons 13 and the latch rods 81 include a plurality of spaced parallel shafts 83 mounted on the under side of the board 21. In the particular case illustrated in the drawings, I have shown five full length shafts 83 and two 15 axially aligned short shafts 84 and 85. The shafts 83, 84 and 85 are supported by suitable brackets 86 attached to the under side of the board 21. Projecting fingers 87 are provided on the several shafts 83, 84 and 85 to extend under 20 and be depressed by the buttons 13. Angle irons 88 may connect spaced fingers of certain of the shafts to be engaged by the buttons 13 so that any button in a particular row is operable to turn a certain shaft. In other instances, fingers 87 of 25 two spaced shafts 83 may extend under a single button 13 so that that button is operable to turn both of the shafts. Two spaced shafts 83 and 85 may be interconnected by links 89 so that operation of one shaft causes operation of the other. 30 The short shaft 84 is operable independently of the other shafts, but may be turned by an adjacent shaft 83 having an arm 90 engaging a finger board 91 of the shaft 84. With the arrangement and relationships just described, depression 35 of certain buttons 13 may cause turning of only one shaft, while depression of other buttons 13 may cause turning of a plurality of shafts.

Each of the latch rods 81 is operatively connected with a shaft 83, 84 or 85. Cooperating 40 arms 92 are provided at the adjacent ends of the shafts and the latch rods 81 and are normally retained in cooperation by springs 93. The springs 93 further aid in retaining the shafts 83, 84 and 85 in positions where their fingers 87 45 and boards 88 may be actuated by the buttons 13. Depression of a button 13 upon being struck with the weight 28 causes turning of a shaft or shafts, for example, the shaft 84 which results in turning of latch rod 81 in a direction to disengage its 50 finger 82 from the end of a gate 73. The spring 79 then shifts the gate to a position where coins or tokens are discharged through the opening 76. The shafts that are interconnected by the links 89 or in other manners turn in unison to cause 55 opening of two or more gates 73. This, together with the differences in the lengths of the openings 75 in the gates causes different numbers of coins or tokens to be paid off when the different buttons 13 are struck.

The invention includes means for resetting or closing the gates 73 near the end of each cycle of operation. The resetting means includes a lever 100 pivotally attached to the lower side of the board 21 and located below the shafts 83. 65 A cam 101 is provided on the substantially horizontal shaft 54 to operate or pivot the lever 100 once during each operation of the device. A spring 102 holds the lever 100 in the normally inoperative position and operates to return the 70 lever to its normal position after operation by the cam 101. Three links 103 are pivotally attached to the outer end of each arm of the lever 100 and extend toward the three gates 73 at each end of the structure. Rods 104 are at- 75

tached to the lugs 80 of the gates and are slidable in openings in flanges 105 on the ends of the links 103. Nuts 106 are provided on the rods 104 to be engaged by the flanges 105 in the event that 5 a gate 73 has been opened and the lever 100 is turned. If the device is operated without causing opening of one of the gates 73 the cam 101 operates to pivot the lever 100, which causes the flanges 105 to slide along the rods 104 without 10 moving or interfering with the gates 73. In the event that a gate 73 has been opened, its spring 79 has shifted it to a position where the nuts 106 on the rod 104 are in engagement with the flange 105. Turning of the lever 100 results in longitudinal movement of the rod and gate 73 so that 15 the gate is returned to its original position where the finger 82 of the latch rod may fall into holding engagement with the end of the gate. In this manner, the gate or gates that may have 20 been opened are automatically closed near the end of each cycle of operation.

The manual control means 15 is manually operable to stop turning of the pile driver 11 and to stop lowering of the boom 26 so that the player 25 may position or attempt to position the boom so that the weight 28 will drop upon a particular button 13. The manual control means 15 includes a rotatable knob or handle 108 projecting from the front of the cabinet 10 and carried on a substantially horizontal shaft 109. The shaft 109 carries a pinion 110 for driving a gear 111. The inner end of the shaft 109 and the shaft of the gear 111 may be carried by a suitable bracket 112 projecting downwardly from the under side of 30 the board 21. A crank pin 113 is provided on the gear 111 to operate a crank 114. The upper end of the crank 114 is pivotally connected with a vertically slidable rod 115. The rod 115 projects upwardly through an opening in the board 35 21 and is provided with an arcuate stop 116. The stop 116 is curved about the axis of rotation of the pile driver 11 and is guided for vertical movement by a bracket 117. The upper edge of the stop 116 is toothed or provided with a plurality of notches 118. A knife or blade 119 projects forwardly from the lower end of the boom 26. The handle 108 may be turned to raise the stop 116 into engagement with the blade 119 during lowering of the boom 26 and turning of the pile 40 driver 11. It is preferred to proportion and relate the parts so that the stop 116 cannot be brought into contact with the blade 119 prior to actuation of the mechanism, that is, prior to turning of the pile driver and lowering of the boom 26. It will 45 be apparent how the stop 116 may be moved upwardly or adjusted so that the blade 119 will cooperate with a notch 118 to stop turning of the pile driver 11 and to stop the downward movement of the boom 26. The means for turning the pile driver 11 and for lowering the boom 26 is such that the stopping of the pile driver and boom 26 in positions where the weight 28 may be centered or disposed directly above a given button 13. In this manner, the player may employ his skill 50 in governing the device in an attempt to receive a large number of coins or tokens.

The coin control means 16 normally maintains the energizing circuit of the motor M open or broken, and is operable by a coin or token to complete the energizing circuit to cause actuation of

the device, and upon the termination of the cycle of operation, is adapted to again break the energizing circuit. The coin controlled means 16 includes a fixture 120 on the front of the cabinet 10 carrying a slide 121 operable to carry a coin or token into the cabinet 10. When a coin is placed in the slide 121 and the slide is pushed inward, the coin or token falls into a chute 122. A trip or pivoted catch 123 has an arm extending into the lower end of the chute 122 to be engaged or struck by the falling coins or tokens. A latch 124 is pivotally mounted below the catch 123 and has shouldered cooperation with the catch to normally retain the catch or trip in a position where its arm projects into the chute 15 122. The trip or catch 123 is pivotally mounted on the lower end of a lever 125 and the catch 123 and latch 124 are maintained in cooperation by a spring 126 attached to one end of the lever. Other springs 127 may be attached to the catch 20 123 and the latch 124 to assist their cooperation and to aid in resetting them as will be herein-after described. A contact 128 is provided on the upper end of the lever 125 and has electrical connection with one lead 129 of the energizing 25 circuit for the motor M. A stationary spring contact 130 is mounted forward of the upper end of the lever 125 and is connected with the other lead 131 of the circuit. The latch 124 cooperates with the catch 123 to normally retain the 30 lever 125 in a position where the contacts 128 and 130 are spaced apart. Upon a coin or token striking the arm of the catch 123, the latch and catch are disengaged and the spring 126 pivots the lever 125 to bring the contact 128 into engagement with the contact 130 so that the motor M is energized to actuate the mechanism.

The invention includes means for resetting or relatching the coin controlled means 16 at the end of each cycle of operation of the mechanism 40 so that the device is shut off after the weight 28 has fallen. An operative connection is provided between the gate resetting lever 100 and the latch mechanism of the coin controlled means 16. A link 130^a is attached to one end of the 45 lever 100 and is operable to turn a bell crank 131^a. The bell crank 131^a may consist of spaced angularly related arms fixed on a stub shaft 132. A link 133 is pivotally attached to the lower arm of the bell crank 131^a and its lower end is pivotally connected to the latch 124. A suitable counter or counting mechanism 135 may be mounted in a position to be engaged by the pivotal connection of the link 133 and the latch 124. The mechanism 135 is operated upon each operation of the 50 device. When the cam 101 pivots, the resetting lever 100 and the link 133 pivots the latch 124 to a position where it again comes into latching engagement with the trip or catch 123. The spring 102 then moves the lever 100 to its normal 55 position illustrated in the drawings, and the lever 125 is pivoted to break the energizing circuit of the motor M.

Normally, the parts of the pile driver 11 may be in the position illustrated in the drawings, that is, the boom 26 may be in an "up" position and the hammer or weight 28 may be suspended a considerable distance above the board 21. Upon a suitable coin or token being passed into the chute 122 through the fixture 120, the trip or 70 catch 123 is pivoted by the falling coin and is disengaged from the latch 124. This disengagement permits the spring 126 to pivot the latch 125 and bring the contact 128 into engagement with the contact 130. This completes the energ- 75

gizing circuit of the motor M so that the shaft 39 is rotated. Rotation of the shaft 39 results in pivoting of the arm 56 and turning of the pile driver 11. Through the gearing in the frame 22 of the pile driver, the winding drum 32 is rotated and the cam 48 is turned. The cam 48 makes one complete revolution during each operation of the mechanism. At the start of the turning of the cam 48, the cam face 50 engages the lever 49 to hold the boom 26 in the elevated position. The inwardly extending portion of the cam face 50 then comes into engagement with the lever 49 so that the boom 26 is permitted to lower. This lowering of the boom 26 then continues for a substantial portion of the cycle of operation of the device but may be stopped manually by means of the stop 116. During or after lowering of the boom 26 the cam face 51 comes into engagement with the end of the drum shaft 33 to disengage the clutch 46 so that the weight or hammer 28 is permitted to drop upon the board 21. The player or operator may turn the handle 108 to position the stop 116 to be engaged by the lowering blade 119 or may bring the stop into engagement with the blade. This engagement stops turning of the pile driver and lowering of the boom 26. In this manner the player may try to position the weight 28 where it will fall upon a button 13 when the clutch 45 is released. After the weight 28 has fallen, the cam face 51 moves out of engagement with the drum shaft 33 so that the clutch 45 is re-engaged and the line 29 is rewound on the drum to raise the weight 28. The concentric portion of the cam face 50 then actuates the lever 49 to raise the boom 26.

In the event that the weight or hammer 28 strikes a button 13 one or more of the gates 73 are opened in the manner described above to discharge the coins or tokens. The coins or tokens are passed through the chutes 77 into the openings 78 where they are accessible to the player. During the phase of operation of the device after dropping of the weight 28 and opening of the gates 73, the cam 101 pivots the lever 100 to close the open gate or gates 73. It will be apparent how the reclosed gates are again filled with tokens or coins T from the containers 14. Pivoting of the lever 100 results in downward movement of the link 133 and re-engagement of the latch 124 with the trip or catch 123. The spring 102 is adapted to return the lever 100 to its normal position so that the catch or trip 123 is also positioned where its arm projects into the chute 122 and pivots the lever 125 to break the energizing circuit of the motor M. This, of course, stops actuation of the device. When the arm of the trip moves into the chute 122, the device is set for further play or operation.

The present invention provides an amusement device that is particularly attractive in appearance and that is very entertaining. The device is entirely automatic in its operation and does not require the attention of an attendant. The mechanism may be easily removed from the cabinet 10 for adjustment, repair, etc. The device will operate for a long period without requiring refilling of the containers 14, or other attention.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. In an amusement device, a miniature pile

driver having a rotatable body, a boom pivoted to the body and a weight suspended from the boom, means for turning the body and operating boom, and a stop operable into engagement with the boom for stopping turning of the body and operation of the boom.

2. An amusement device including, a turnable body, a boom pivoted to the body, a line engaging over the boom, a weight carried by the line, means for turning the body, means for operating the boom, a single coin controlled means for actuating the two mentioned means, and object dispensing means including an actuating button de-pressible when struck by the weight.

3. An amusement device including, a turnable body, a boom pivoted to the body, a line engaging over the boom, a weight carried by the line, means for turning the body, means for operating the boom, power means for actuating the two mentioned means, a single coin controlled mechanism governing the last mentioned means, and object dispensing means including an actuating button de-pressible when struck by the weight.

4. An amusement device including a dispensing mechanism having an upstanding de-pressible ac- tuating button, a pivoted boom, a line engaging over the outer end of the boom, a weight carried by the line, a winding drum for the line, coin controlled automatic means for operating the boom and drum whereby the boom is lowered and the weight is permitted to drop, and manual means for stopping lowering of the boom so that the player may attempt to cause the weight to strike the button.

5. An amusement device including a turnable body, a boom pivoted to the body, a line operable over the end of the boom, a weight on the line, coin controlled means for turning the body and operating the boom and line, a manually operable toothed stop adapted to engage the boom to stop 40 turning of the body and the lowering of the boom.

6. An amusement device including a boom, a line carried by the boom, a weight suspended by the line, means for controlling movement of the line, a movably mounted button positioned where 45 it may be struck by the weight, and means operable by the button to dispense objects.

7. An amusement device including a boom, a line carried by the boom, a weight suspended by the line, means for pivoting of the boom, 50 means for releasing the line to allow the weight to drop, a de-pressible button positioned where it may be struck with the weight, and an object dispensing mechanism operable by the button.

8. In an amusement device, the combination 55 of a de-pressible button, a miniature pile driver having a weight adapted to strike the button, and an object dispensing mechanism operable by the button including a container for the objects, a shiftable gate at the discharge end of the container, and an operative connection between the gate and button.

9. In an amusement device, a movably mounted button, a manually controllable power driven mechanism having a part adapted to operate the 65 button, and an object dispensing means operable by the button, including a container for the objects, a discharge gate for the container, and a connection between the button and gate.

10. In an amusement device, a plurality of 70 de-pressible buttons, a power operated manually directable device for selectively operating the buttons, and object dispensing means operable by the buttons including containers for the objects, discharge gates for the containers, releasable 75

latches holding the gates closed, shafts operable by the buttons, and operative connections between the shafts and latches.

5 11. In an amusement device, a plurality of depressible buttons, a manually controllable power driven mechanism having a part adapted to strike any one of the buttons, and object dispensing means operable by the buttons including containers for the objects, discharge gates for 10 the containers, the gates being operable to discharge different amounts of objects.

15 12. In an amusement device, a plurality of depressible buttons, a manually controllable power driven mechanism having a part adapted to strike any one of the buttons and object dispensing means operable by the buttons including containers for the objects, discharging gates for 20 the containers, releasable latches holding the gates closed, shafts operable by the buttons, operative connections between the shafts and latches, and means for closing the gates and resetting the latches.

25 13. In an amusement device, a normally idle mechanism, a depressible button for actuating the mechanism, a pivoted boom, a rotatable mounting for the boom, a weight suspended from the boom, means for turning the mounting means and for lowering the boom, and a stop manually operable into engagement with the boom to control turning of the mounting and lowering of the boom whereby the weight may be made to strike the button.

30 14. In an amusement device, a normally idle mechanism, a depressible button for actuating the mechanism, a pivoted boom, a rotatable mounting for the boom, a weight suspended from the boom, means for turning the mounting, means for lowering the boom, coin controlled means for actuating the two means, and a single manually operable means for stopping lowering of the boom and turning of the mounting whereby the weight may be made to strike the button.

35 15. In an amusement device, a normally idle mechanism, a depressible button for actuating

the mechanism, a pivoted boom, a rotatable mounting for the boom, a line depending from the boom, a weight carried by the line, means for turning the mounting, means for pivoting the boom downwardly, coin controlled means for actuating the two mentioned means, and a part manually operable into engagement with the boom to stop turning of the mounting and lowering of the boom whereby the weight may be made to strike the button.

5

10 16. An amusement device including, a depressible button, a mechanism operable by the button, a pivoted boom, a rotatable mounting for the boom, a weight suspended from the boom, a projecting part on the boom, means for rotating the mounting and lowering the boom, a shiftable member having a plurality of spaced notches adapted to receive said part, and manually operable means for shifting the member into engagement with said part so that the part is received 20 in a notch to stop turning of its mounting and lowering of the boom whereby the weight may be made to strike the button.

15 17. In an amusement device, a miniature pile driver having a pivoted boom, and a weight suspended from the boom, means for lowering the boom, a stop normally out of engagement with the boom and movable into engagement with a part on the boom to limit downward movement of the boom, and manual means for moving the 30 stop.

25 18. In an amusement device, a plurality of depressible buttons, a manually controllable power operated device for selectively depressing the buttons, and object dispensing means operable 35 by the buttons including, containers for the objects, discharge gates for the containers, releasable latches holding the gates closed, shafts operable by certain of the buttons, shafts operable by other buttons, means operatively interconnecting certain of the shafts, and operative connections between the shafts and latches whereby 40 operation of the shafts releases the latches.

MURRY MARGOLITH.
